COMPOUND MOULD ENCLOSING PRESS

Edward H. Yukon, South Braintree, and Elwyn F. Bonney, Auburndale, Mass., assignors to Acme Industrial Equipment Company, Boston, Mass., a corporation

Application February 10, 1956, Serial No. 564,743

9 Claims. (Cl. 18—16)

This invention relates to an apparatus for forming molded bodies and, more particularly, to a compound mold enclosing press of the class employing upper and lower platens which are required to be moved into and out of operative engagement with one another in the course of a molding operation.

In one specific aspect, the invention is exemplified by a mold enclosing press of relatively large size involving the application of high pressure, for example, pressures occurring in an order of magnitude of from 50,000 to 60,000 pounds in some cases. In this preferred embodiment, the press is especially designed for cold press operation but may also be utilized in conjunction with the application of heat.

In designing and operating a press of the general class indicated, it is exceedingly important to provide for moving the platen elements of the press into desired positions of adjustment while maintaining a very precise register of the mold surfaces with respect to one another in a closed position of the press. The problem of designing a mechanism which will deal with the pressures indicated and which can perform necessary platen movements in precise register is further complicated by clearance requirements for clearing mold parts, such as elongated mold pins and the like, during separation of these members.

It is a general object of the invention to devise a compound mold enclosing press of the platen type indicated and to provide in such a structure special mechanisms for preventing any displacement of the press parts and for guiding the enclosed mold elements into desired positions of precise register. It is a further object of the invention to provide a special platen movement by means of which the separation of mold pins may be facilitated. Still another object is to combine with the press of the invention a safety locking device for one of the platens, as well as other safety apparatus for protecting press operators from injury during the press movements. Various other objects and novel features will be further apparent from the detailed description of the invention herein-after set forth.

To deal with the problems and objectives outlined, we have conceived of the idea of combining a pivotally supported upper press platen and mold assembly with a vertically movable lower press platen and mold assembly in operatively connected relationship to one another. In this arrangement, the vertically movable lower press platen, during movement, is constantly guided along a predetermined vertical path which maintains exact register of this member with the pivoting upper platen.

We have further found that, in thus combining the two platens in operatively connected relationship, we may desirably employ a novel sequence of movements for separating pin type molds with a minimum of difficulty and lost motion, and we may also provide for highly desirable adjustability features. We have also devised special safety apparatus particularly designed for the combination of upper and lower platens noted and use-

2

ful in guarding an operator during the operation of these press platens in their joined-together association.

These features are illustrated in one preferred form in the accompanying drawings, in which:

5 Fig. 1 is a plan view of the mold enclosing press of the invention;

Fig. 2 is a front elevational view of the structure shown in Fig. 1;

10 Fig. 3 is a side elevational view further illustrating an upper platen and mold unit in a raised position;

Fig. 4 is a view similar to Fig. 3 but showing the upper platen and mold unit lowered into a horizontally disposed position;

Fig. 5 is still another side elevational view similar to

15 Figs. 3 and 4 but also indicating in broken lines a lower platen and mold unit in engaged relationship with the upper platen and mold unit;

Fig. 6 is a plan view showing the platen supporting structure of the invention with the upper and lower 20 platens and mold units removed therefrom;

Fig. 7 is a cross-section taken on the line 7—7 of Fig. 5;

Fig. 8 is an enlarged fragmentary cross-sectional view of upper and lower mold members in an engaged operative position;

25 Fig. 9 is a cross-section taken on the line 9—9 of Fig. 2;

Fig. 10 is a fragmentary side elevational view of 30 pneumatic safety locking means with portions broken away to illustrate in cross-section spring holding mechanism for the pneumatic safety lock.

The apparatus shown in these figures generally includes as principal parts thereof a platen supporting structure; upper and lower platen and mold units mounted in the platen supporting structure; a pair of hydraulic actuating members connected between the two platens to selectively control their movements; and special guide and register mechanisms for maintaining the platen in correctly registered relationship to one another during 35 their travel in carrying out a press operation. These parts are, in general, designed to carry out a press operation in which stock to be processed is placed in the lower platen and mold unit and thereafter the two platens and mold units are forced against one another and subsequently disengaged.

Considering first the platen supporting structure, attention is directed to Figs. 1—3 and 6. As noted, especially in Fig. 6, we provide a base, generally denoted by arrow B and consisting of a framework made up of angle iron pieces 1, 2, 3 and 4 suitably joined together by metal gussets 5, 6, 7 and 8 welded or otherwise secured. To this base is solidly attached two sidewalls 9 and 10 which may be formed, for example, with flanged bottoms 9a and 10a. These sidewalls extend upwardly, as shown in Fig. 3, and running between the two sidewalls is a front wall 11 which, as shown in Fig. 2, is relieved along its upper intermediate portion to better furnish access to the press interior.

These sidewalls 9 and 10 at their upper portions are 50 constructed with specially formed sections for receiving the upper platen. Thus, for receiving the upper platen and mold unit, the walls 9 and 10 are constructed with upper extensions 9c and 10c (Figs. 1 and 3). In these upper extensions are located bearings as 12 and

55 14 (Fig. 1) having fixed therein stub shafts as 16 and 18 on which are pivotally mounted hinge members 20 and 22.

The hinges 20 and 22 are solidly secured to and support an upper platen 24 of the rectangular shape indicated 60 which has connected to it a mold member 25, as best shown in Fig. 1. The hinges constitute a pivotal mounting for rotating the upper platen and mold into a raised

position, such as shown in Fig. 3, and back into a horizontally disposed position, as shown in Fig. 4.

In the latter horizontally disposed position, the platen 24 is, in accordance with the invention, received and completely supported upon horizontally extending bearing edges 9d and 10d formed in the sidewalls 9 and 10. One of these edges, 9d, is most clearly shown in Fig. 3. We may also desire to employ stops as 26 (Fig. 5) located at the underside of the upper platen and capable of vertical adjustment therein. It will be observed that we have shown the upper mold 25 provided with elongated pins, although it will be understood that the invention is not limited to this arrangement.

Mounted for vertical reciprocating movement in the sides 9 and 10 is a lower platen 28 and mold member 29, having the generally rectangular shape shown in the drawings and including a box-like enclosure. This structure is provided with a mold supporting plate 30. When the lower platen is in a bottom position, the entire weight of the platen 28 and mold 29 is, in accordance with the invention, supported through this mold supporting plate 30 upon a plurality of stop elements 32, 34, 36 and 38.

The stop elements noted are vertically adjustable and constitute an important feature of the invention. For example, in one preferred form, the stops may include internally threaded hollow posts in which are threaded extension pins 32', 34', 36', 38'. By varying the position of the extension pins, very desirable adjustments may be made in the height of the lower platen and mold unit relative to the base. This is advantageous in enabling an operator to locate the unit in the most effective working position and offers a flexibility feature not, so far as we are aware, found in molds of this heavy construction type. Moreover, such an adjustment feature is exceedingly useful in accommodating the press to take a range of differently sized mold members and thereby generally broadening its capacity.

The upper and lower platen and mold units now described are, in accordance with the invention, combined in operative connected relationship, as shown in Figs. 3, 4, 5 and 7, by means of two specially devised hydraulic actuating members. These hydraulic actuating members are denoted by numerals 40 and 42 and consist of double-acting hydraulic cylinders of the conventional type which may operate on compressed air, for example.

Each of the members 40 and 42 has its two extremities connected between the ends of respective upper and lower platens. For instance, member 40 is pivotally pinned to respective platen extensions by pins as 41 extending through clevis portions 43 and 44 (Fig. 7) of platen 24, and by pins 45 extending through heavy specially formed clevis parts 46 and 48 integral with the ends of lower platen 28, shown in Figs. 3-5 and 7.

It will be understood that similar clevis portions and pins are provided at opposite ends of the upper and lower platens for the member 42. It will also be understood that each of the hydraulic actuating members 40 and 42 is provided with suitable conduit means for furnishing a fluid, such as compressed air, and, since this type of apparatus is well-known to the art, it has not been shown in detail in the drawings.

It will be observed that, by thus connecting the two platens together, it becomes possible to carry out several unique positioning steps. Thus, with the lower platen in a bottom position and resting upon the stops 32, 34, 36 and 38, it will be seen that the hydraulic members 40 and 42 may be actuated to raise the upper platen and rotate it into the position shown in Fig. 3 and thus open the press for loading purposes.

Thereafter, the hydraulic members 40 and 42 may be operated to swing the upper platen down into a horizontally disposed position in which this upper platen rests upon the bearing edges 9d and 10d, as shown in Fig. 4, and the elongated pins of the mold 25 extend vertically downwardly.

When thus supported, the upper platen comprises an anchoring means for holding the hydraulic members 40 and 42 at their upper ends and these members 40 and 42 may then be actuated to lift the lower platen into the closed position illustrated in Fig. 5, and the lower mold 29 moves vertically upward engaging around the elongated pins of the top mold 25. By reversing these movements, it will be obvious that the pins may be disengaged without jamming.

- 10 It will be further apparent that, in moving these relatively heavy platen units in the manner suggested, it is important to maintain precise register of the upper and lower molds as they move into a closed position. With this in mind, we have combined with the lower platen 28 15 special guide means, including vertical racks 50 and 52 which are fastened to the inner surfaces of the sidewalls 9 and 10, as illustrated in Figs. 6 and 9. These racks extend over a distance slightly exceeding the vertical travel of the lower platen 28 and have in mesh therewith gears 20 54 and 56 free on opposite ends of a shaft member 57. The latter shaft 57, as shown in Fig. 6, is furnished with guide rollers 58 and 60 which are received in vertical slots as 62 formed through the sidewalls. The guide rollers 58 and 60 are preferably formed with flanged edges, as 25 shown in Fig. 6, which are adapted to overlie opposite surfaces of the respective walls 9 and 10. Also mounted in these vertical slots are upper guide rolls 64 and 66 on shaft 67, likewise extending through the lower platen member.
- 30 By means of these guide members, vertical movement of the lower platen induced by the hydraulic actuating members 40 and 42 is constantly guided by the gear and 35 rack mechanism so that contact surfaces of the mold 29 will also occur in true parallelism and in squared relationship with respect to contact surfaces of the upper mold 25. Simultaneously, the guide roll flanges working on opposite surfaces of the sidewall members maintain 40 substantially constant axial positioning of the shaft 57 and thus longitudinal displacement of the lower platen and mold relative to the upper platen and mold is prevented.

In addition to the accuracy requirements required in a machine of this class, it is extremely important to prevent, wherever possible, injury to press operators during the movements of the platen members. For example, 45 in raising the top platen into the position shown in Fig. 3, we combine with the upper platen a positive mechanical locking means for holding this platen in a raised position. This locking means is constantly seeking to move 50 into a locking position and must be continuously held in a released position during the stop of lowering the upper platen from a raised position. This novel locking means includes a pair of arcuate rack portions formed at the two upper extremities of the sidewalls 9 and 10 and indicated by the teeth 9f and 9g.

To engage with these arcuate rack portions, we provide pawl members as 60 which are pivotally supported, as 55 shown in Fig. 9, for example, on pins as 62 in bracket members 64. The upper ends of these pawl members project through openings as 65 in the top of platen 24 and are pivotally connected at 66 to a hydraulic plunger 67 forming a part of a hydraulic cylinder 68. The plunger, as shown in Fig. 10, is resiliently held by a spring 69 in the hydraulic cylinder is a position such 65 that it constantly seeks to move the pawls into engagement with their respective rack teeth.

By moving the plunger 67 through suitable hydraulic circuit means, the pawls may be pivoted in a counter-clockwise direction, as viewed in Figs. 9 and 10, and the 70 lower ends of these pawls may thereby be held out of engagement with the corresponding teeth on the arcuate rack portions while the platen is being lowered. It will be apparent that, when the upper platen 24 is raised, the action of the spring 69 will merely hold the pawls against 75 the rack teeth and they will slide over these members

without interference. However, if, at any point during the raising operation, the hydraulic system should fail, the spring 69 automatically insures locking the pawls into place to prevent the platen from dropping back. The pawls can be disengaged by actuating the hydraulic cylinders 68 which force the pawls out of contact with their respective racks.

A further safety device included in the press prevents an operator from being caught between the front wall 11 of the platen supporting structure and the bottom edge of the lower platen 28 when the latter member is being moved from a raised position to a bottom position. We accomplish this by mounting on the front wall of the platen supporting structure a protective apron or plate 70 (Figs. 3, 4, 5) which is hinged at 72 in a position such that it will be contacted by a portion of the lower platen as this member rises into a position such as shown in Fig. 5. Under such conditions, the protective apron 70 will have been swung upwardly about a horizontal axis of hinging, as suggested in broken lines in Fig. 5, and in this position it is impossible for an operator to have any part of his body extending into the space between the lower platen and the front wall of the platen supporting structure. As the lower platen drops down into a bottom position, as illustrated in Fig. 4, the protective apron follows the platen down and assumes the position shown in Fig. 4, which continues to close the space between the platen and the platen supporting structure front wall.

We have also provided means tending to prevent an operator from being caught between one of the vertical stops 32', 34', 36', 38' and the bottom of the lower platen. This means includes telescoping rods 32a, 34a, 36a and 38a which are fixed to the underside of the lower platen and which slide in the hollow adjustment posts and the platen moves up and down.

From the foregoing description, it will be evident that we have provided a unique combination of vertically reciprocating and rotatable platens by means of which a range of mold constructions may be conveniently employed. It is particularly pointed out that, in the case of carrying out a press operation with a mold which involves a plurality of elongated members, such as spaced-apart pins, it becomes possible to disengage the pins without interference and still carry out desirable rotative movement of the upper platen. This is accomplished by dropping the lower platen and mold from a closed position which clears the pins and then swinging back the upper platen into a fully open position.

The adjustability features of the lower platen is particularly advantageous in adapting the machine to varying operator requirements, as well as to accommodating a range of lower mold sizes. It is also apparent that these novel movements and mechanism are combined in a manner such that a safe, dependable operation can be carried out regardless of whether the hydraulic system becomes inoperative.

While we have shown preferred embodiments of our invention, it should be understood that changes and modifications may be resorted to within the scope of the appended claims.

Having thus described our invention, what we claim is:

1. In a press construction, a platen supporting enclosure having a base and sidewalls extending upwardly from either side thereof, an upper platen and mold member mounted for rotation about a horizontal axis between the said sidewalls, bearing edge means formed in the sidewalls for rigidly supporting the upper platen and

mold member when it is swung into a horizontally disposed position, a lower platen and mold mounted for vertically reciprocating movement in the said sidewalls, vertically extending stop means anchored in the base 5 to receive the said lower platen and mold in one position of adjustment thereof, a pair of hydraulic actuating members pivotally connected between the upper and lower platens and power-driven means for actuating said hydraulic members to raise the lower platen and mould 10 into a fully closed position in which it occurs in suspended relationship with respect to the upper platen and mould when the latter members are horizontally disposed.

2. A structure as defined in claim 1 in which the said vertically extending stop means for the lower platen are 15 adjustable to vary the bottom position of the said lower platen.

3. A structure according to claim 2 in which the vertical stop means include telescoping guide rods movable with the lower platen.

20 4. A structure as defined in claim 1, including a gear and rack mechanism for causing the surface of the lower platen mold to remain in a substantially constant horizontal plane during its vertical movement.

5. A structure as defined in claim 1, including a shaft 25 located between the sidewalls, a gear and rack mechanism operated by said shaft for guiding the lower platen and mold during vertical movement and a guide shaft and guide roll apparatus supported on the lower platen and located in rolling engagement with one of the side walls for preventing axial displacement of the lower platen.

30 6. A structure according to claim 1, including safety ratchet means for holding the upper platen as it is rotated through into successive raised positions.

35 7. A structure as defined in claim 1 in which the sidewalls are formed with upwardly extending arcuate ratchet portions, and the said top platen includes pneumatically operated pawls constructed and arranged to selectively engage the ratchet portions in any desired position 40 of rotatable movement of the upper platen and hydraulically lock the platen against accidental release.

45 8. A structure according to claim 1 in which the sidewalls are formed with upwardly extending arcuate ratchet portions, said top platen including pneumatically operated pawls constructed and arranged to slidably engage over the teeth in the ratchet portion during downward rotative movement of the upper platen and said hydraulically operated points being under the control of a pair of spring-loaded pneumatic cylinders which selectively engage the pairs against their respective ratchet portions 50 when the hydraulic actuating members are inoperative.

9. A structure as defined in claim 1, including a safety apron hinged at the front of the platen supporting structure in a position excluding insertion of an object between the front edge of the structure and the lower platen during vertical reciprocation of the latter member.
